UNITED STATES PATENT OFFICE.

EDGAR H. FREEMAN, OF TRENTON, NEW JERSEY, ASSIGNOR TO E. H. FREEMAN ELECTRIC COMPANY, A CORPORATION OF NEW JERSEY.

COMBINATION PORCELAIN SOCKET.

1,283,491.

Specification of Letters Patent.

Patented Nov. 5, 1918.

Application filed April 11, 1917. Serial No. 161,273.

To all whom it may concern:

Be it known that I, EDGAR H. FREEMAN, a citizen of the United States, residing at Trenton, in the county of Mercer and State 5 of New Jersey, have invented certain new and useful Improvements in Combination Porcelain Sockets, of which the following is a specification.

This invention relates to electrical tap-10 sockets and more particularly to a socket of this type embodying a key switch mechanism whereby the same may subserve the usual functions of a key socket, as well as providing simple and practical means for 15 tapping the current from the socket for supplemental uses.

To this end, the invention has in view a novel construction of key socket wherein one set of terminals is controlled by the key 20 switch, while a second set of terminals are constantly "live" and entirely independent of the other whereby current may be always tapped off therefrom regardless of the position of the switch key. That is to say, the 25 present invention contemplates a socket construction wherein one set of terminals is controlled by a switch key, while the other is not, so that the socket may perform the usual functions of a key socket in connection 30 with the ordinary incandescent lamp or other electrical fitting having a screw plug, as well as subserving the additional function of supplying current to a branch line for any other electrical purpose, through the 35 medium of a readily attachable and detachable tapping plug.

A further object of the invention is to provide a novel and practical socket construction which can be economically manufactured and easily assembled, and is of a substantial and permanent character for the 40 purposes specified.

With the above and other objects in view which will more readily appear as the nature 45 of the invention is better understood, the same consists in the novel construction, combination and arrangement of parts hereinafter more fully described, illustrated and claimed.

50 A preferred and practical embodiment of the invention is illustrated in the accompanying drawings, in which—

Figure 1 is a perspective view of the improved socket.

55 Fig. 2 is a vertical sectional view partly

in elevation showing the switch mechanism and its relation to the center contact of the receptacle terminals.

Fig. 3 is a vertical sectional view partly 60 in elevation taken at right angles to Fig. 2.

Fig. 4 is a horizontal sectional view of the insulating body plug showing the supplemental line terminals and the tapping plug about to be moved into contact therewith.

Fig. 5 is a cross sectional view on the line 65 5—5 of Fig. 2.

Fig. 6 is a bottom plan view of the cap piece showing the line wire terminals.

Similar reference characters designate cor-70 responding parts throughout the several figures of the drawings.

In carrying the present invention into effect, it is proposed to construct the socket body proper of porcelain, though, it will, of course, be understood that the improvements 75 herein specified may be readily adapted to a metal shell type of socket with suitable provisions for insulation. Accordingly, by reference to Fig. 1, of the drawings, it will be observed that the present socket essentially 80 and preferably comprises a porcelain or equivalent insulating body block designated generally as 1, a porcelain or equivalent receptacle element 2, and a porcelain or equivalent cap element 3, which are held in their 85 assembled relation by means of suitable fastening screws which are also current carrying conductors as will herein more fully appear.

Referring to Fig. 2, it will be seen that 90 the insulating body block 1 is provided with a suitable switch chamber C having therein a switch mechanism preferably comprising in its organization a substantially U-shaped switch frame 4 having journaled in its opposite upstanding arms a conventional switch spindle 5 provided at one end with a rotatable switch block 6 and at the other end with an operating key 7. The switch block 6 is adapted to close the circuit between a 95 spring contact member 8 connected with one of the line wire terminals A carried by the cap element 3 as will hereinafter more fully appear, and a tension spring 9 which causes the switch block to make a quick break in 100 opening the circuit. This tension spring 9 is electrically connected with the center contact 10 of the receptacle, by means of a combined conducting and holding screw 11 which not only serves to hold the center contact 110

member 10 and switch frame 4 in position, to clamp one end of the tension spring between the frame, and body block, but also holds the receptacle element and insulating body block in assembled relation, independent of the cap, so that the latter may be separately handled to secure the line wires to the main line wire terminals A and B respectively.

10 Referring further to the receptacle element 2, it will be observed that the same houses the screw shell contact 12 which is held in position therein by means of the fastening screws 13 co-operating with the 15 usual horseshoe shaped washer plate 14. Thus, the receptacle terminals are the usual center contact spring 10 and screw shell contact 12, the former being electrically connected with one of the line wire terminals of 20 the socket only when the switch block 6 is in closed position. To provide for supplying current to the screw shell contact 12, the latter is in metallic contact with a relatively long "live" conducting and fastening screw 25 15, shown in Fig. 3 which extends through the closed end wall of the receptacle element and entirely through the body 1 to connect with the line wire terminal plate B in the cap piece. Therefore, it will be apparent 30 that a circuit will be completed through the receptacle terminals 10 and 12 when the switch block 6 connects the contact plates 8 and 9. That is to say, the current will pass from the terminal A through the switch 35 mechanism to the screw 11, center contact 10 to the lamp or other electrical device, and thence back to the shell 12 and through the screw 15 to the other line wire terminal B.

In connection with the insulating body 40 block 1 and receptacle 2, it will be observed from Figs. 1, 4, and 5 that the same are formed at one side thereof with a flattened plug seat S, which is pierced by the guide openings or channels G that are adapted to 45 receive the tapping plug contacts which engage with the spring supplemental line terminals. That is to say, in addition to the switch chamber C, the body block 1 is provided with the parallel guide openings G 50 that communicate with the enlarged housing chambers H, which accommodate therein the angular or equivalent supplemental line terminal springs 16 and 17 respectively adapted to engage with the spaced tapping 55 plug contacts F carried by the line-tap plug designated generally as T. These supplemental line terminal springs 16 and 17 respectively, are mounted on the angular attaching brackets 18 and 19, which are respectively engaged by, and in electrical contact with, the relatively long metallic conducting screws 15 and 20. The latter screw 20, however, has no electrical connection with either of the terminals in the receptacle 60 element, but has its upper end in engage-

ment with the spring contact member 8, that is associated with the main line wire terminal A. Therefore, since the conductor screw 15 is in electrical contact with the main line wire terminal B, it will be apparent 70 that current will be supplied to both of the supplemental line terminals 16 and 17 through their respective brackets 18 and 19, because both screws 15 and 20 are constantly "live," the same being permanently in electrical contact with both of the main line wire terminals A and B.

The cap element 3 of the socket essentially embodies in its organization an insulating cap piece 21 which carries on one face thereof, the main line wire terminals A and B, previously referred to, while the other face thereof is fitted with a metal covering cap 22 which is held to the insulating body by means of suitable brackets 23 and fastening 80 screws 24. This metal covering cap 22 is fitted with the usual fixture nipple 25 for securing the socket to the end of a conduit or the like. Fig. 6 of the drawings shows the main line terminals A and B in plan, 90 and as will be observed, these terminals are each of angular formation having the line wire binding screws 26 fitted to the body portion thereof, while the angularly disposed portion 27 thereof is provided with a 95 suitable opening 28 for receiving the threaded end of its corresponding conductor member 15 or 20, as the case may be.

In connection with the main line wire terminal A, it will be observed that the spring 100 contact member 8 which constitutes a part of the electrical connection between the line wire terminal A and the center contact of the receptacle, may be clamped between the insulating body 1 and the foot 27 of the 105 terminal A, and held in place by the threaded end of the conductor screw 20. Since both of the conductor screws 15 and 20 have their head portions clamping one side of the bottom of the screw shell chamber in the receptacle element, and their opposite ends threaded into the line wire terminals A and B, it will be apparent that these screws, in addition to providing electrical connections between the line wire terminals and the supplemental line terminals, 110 serve to hold the cap and receptacle elements in assembled relation to the body block. It has already been pointed out that the conductor screw 11 holds the body and 115 receptacle together, but the conductor screws 15 and 20 constitute the means for holding the cap element 3 to the body, because of their threaded engagement with the line wire terminals which are rigidly carried 120 by the porcelain cap piece 21 of the cap.

From the foregoing, it will be apparent 125 that the present construction provides a socket having both receptacle and line tapping terminals, the latter being permanently 130

in electrical contact with the line wire terminals A and B, while one of the connections for the receptacle or lamp contacts include a switch mechanism, which is capable of 5 rendering the said contacts live or dead according to the position of the switch. That is to say, current for the receptacle terminals will pass from the line wire terminal A, through the contact spring 8, switch block 10, spring 9, screw 11 and center contact 15. However, both the supplemental line 15 terminals 16 and 17 are always "live", and therefore, ready for use regardless of the position of the switch, because of their connection with the constantly live conductors 15 and 20. The conductor 20, however, is 20 entirely insulated from the terminals, as already explained.

Without further description, it is thought that the many features and advantages of the present invention will be readily apparent, 25 and it will, of course, be understood, that the same consists in the novel construction, combination and arrangement of parts hereinafter more fully described, illustrated and claimed.

30 I claim:

1. An electrical tap key-socket including an insulating body block, a cap carrying line wire terminals, a receptacle element carrying the lamp terminals, a switch mechanism mounted in the body block and electrically connected with the line wire terminals and with the lamp terminals, and constantly live line tapping terminals mounted in the body block and having a detachable connection with the line wire terminals.

2. In an electrical tap key-socket including an insulating body block, a cap carrying the line wire terminals, a receptacle element carrying the lamp terminals, a switch mechanism for controlling the current to the lamp terminals, line tapping terminals carried by the body block, and fastening elements connecting the line wire terminals and the line tapping terminals and arranged

40 as coupling members for holding the cap in position.

3. An electrical tap key-socket including a cap having main line wire terminals, a body block, a switch mechanism in the body 50 block, a contact for the switch mechanism

in electrical connection with one of the main line wire terminals, a receptacle element, contacts in the receptacle, means for connecting one of said contacts with the switch mechanism and holding the receptacle and body together, elements for clamping the cap and receptacle to the body block and electrically connected with the main line wire terminals, one of said elements connecting one of the main line wire terminals with 60 one of the receptacle contacts, and constantly live supplemental line terminals in electrical connection with said elements for clamping the cap and receptacle to the body.

4. An electrical tap key-socket including 70 an insulating body block, a cap carrying main line wire terminals at one end of said block, a receptacle element at the other end thereof and having lamp terminals, a single switch mechanism electrically connected 75 with one of the lamp terminals and with one of the main line wire terminals, live conductors carried by the body block and detachably connected with the main line wire terminals, thereby holding the cap in position, one of the said conductors connecting 80 with one of the lamp terminals and constantly live supplemental line terminals carried by the conductors.

5. An electrical tap key-socket including 85 an insulating body block having a switch chamber in one face and separate supplemental line terminal chambers in the other face, a cap carrying the main line wire terminals, a receptacle having lamp terminals, a 90 switch mechanism in the switch chamber, a conductor screw coupling the receptacle and body block and also providing electrical connection between the switch mechanism and one of the lamp contacts, combined conducting and holding screws clamping the receptacle to one end of the body block and engaging the main line wire terminals in the cap to hold the latter to the body block, one of said screws connecting one of the main 95 line wire terminals and one of the lamp contacts, and supplemental line terminals located in the said terminal chambers of the body.

In testimony whereof I hereunto affix my 105 signature in the presence of two witnesses.

EDGAR H. FREEMAN.

Witnesses:
